(57) **CLAIM**

The ornamental design for a communication headset, as shown and described.

DESCRIPTION

FIG. 1 is a perspective view of a communication headset showing my new design;

FIG. 2 is a left side elevational view thereof;

FIG. 3 is a right side elevational view thereof;

FIG. 4 is a front view thereof;

FIG. 5 is a rear view thereof;

FIG. 6 is a bottom view thereof;

FIG. 7 is a top view thereof; and,

FIG. 8 is an enlarged perspective view of the flexible transparent ear tube portion as illustrated in FIG. 1, shown separately for purposes of illustration.

The broken lines form no part of the claimed design.
